UNITED STATES PATENT OFFICE.

HUGO GERNSBACK, OF NEW YORK, N. Y.

ELECTRICAL SWITCH.

Application filed September 18, 1924. Serial No. 738,539.

This invention relates to electrical switches.

An object of the invention is the provision of a switch having a movable plunger 5 adapted to be retained between a pair of spring contact arms when the switch is in operative position.

A further object is to provide a coil spring surrounding the plunger which is 10 placed under tension when the plunger is projected and which will move the plunger to an inoperative position as soon as the end of the plunger is disengaged from the spring contact arms.

15 In the accompanying drawings I have shown one embodiment of the invention. In this showing,

Figure 1 is a perspective view of the switch,

20 Figure 2 is a vertical sectional view showing the switch mounted on a panel, and,

Figure 3 is a perspective view of the spring contact arms removed, and

25 Figure 4 is a central, vertical, sectional view through the movable element of the switch removed from the panel.

Referring to the drawings the reference numeral 1 designates a base or block of suitable insulating material having a 30 threaded opening 2 formed therein. A pair of arms 3 are arranged on the back of the block and secured thereto by means of bolts 4. The ends of the bolts project from the back of the block and are adapted to receive 35 nuts 5 forming binding posts for lead wires (not shown). As shown the terminals of the spring arms are extended over the ends of the block as indicated at 6. The block is adapted to be arranged in the rear of a 40 panel 7 which is provided with an opening 8 in alignment with the opening in the block. The arms 3 extend at an angle from the rear face of the block toward each other as indicated at 9 and are provided with offset ends 10.

A plunger is mounted in the openings in the block and the panel and is adapted to bridge the space between the ends 10 of the spring contact arms when the switch is in closed position. As shown a sleeve nut 11 is arranged in the openings 2 and 8 and is provided with external threads to engage the internal threads formed in the opening 2. A washer 12 surrounds this nut and the nut is provided with an enlarged head 13 which contacts with the outer face of the

washer. A plunger is mounted within the nut and the plunger consists of a handle portion 14 and an inner portion 15. As shown, the handle portion is provided with 60 a head 16 on its outer end to facilitate operation of the switch and intermediate the ends it is provided with a collar 17 which is adapted to engage the head 13 of the nut to limit the inward movement of the plunger. 65 The inner end of the handle portion of the plunger is provided with a central threaded bore 18 adapted to receive a threaded portion 19 formed on the inner portion of the plunger. A coil spring 20 is arranged within the nut beneath the inner end of the handle portion of the plunger. The inner portion of the plunger is provided with an enlargement or ball 21 on its inner end adapted to engage the ends 10 of the spring 70 contact arms when the switch is in the operative position shown in full lines in Figure 2 of the drawings.

The operation of the device will be apparent from the foregoing description. When 80 the switch is to be turned on the plunger is moved inwardly to the full line position shown in Figure 2 of the drawings. The space between the ends 10 of the spring contact arms is normally less than the diameter of the ball 21 as shown in dotted lines in Figure 2 of the drawings whereby the inward movement of the plunger forces the arms out under tension and causes them to engage the ball 21 and hold the plunger 85 in its inner position. While in this position the coil spring 20 is placed under tension. When the switch is to be turned off the plunger is moved outwardly and as soon as the head 21 becomes disengaged from the ends 10 of the spring contact arms the 90 spring 20 moves the plunger outwardly to its limit as indicated in dotted lines in Figure 2 of the drawings to insure breaking 95 the circuit.

100 It is to be understood that the form of my invention herewith shown and described is to be taken as a preferred example of the same and that various changes in the shape, size, and arrangement of parts may be resorted to without departing from the spirit of the invention or the scope of the subjoined claim.

Having described my invention, I claim: 105
In a device of the character described, a base having a threaded opening, a sleeve nut mounted in said opening, a plunger

2
mounted in said sleeve, said plunger comprising a handle portion and an inner portion smaller in diameter than the handle portion, the inner end of said handle portion being provided with a threaded bore adapted to receive the end of said inner portion, a spring arranged in said sleeve nut surrounding the inner portion of said plunger and adapted to engage the end of said handle portion to normally maintain the

plunger in its outer position, and a pair of spring contact arms arranged on the rear of said base, the ends of said arms being spaced from each other a distance less than the inner end of said plunger whereby said arms will be placed under tension when said plunger is moved inwardly and will retain said plunger in said position.

In testimony whereof I affix my signature.
HUGO GERNSBACK.
